US00D604662S

(12) **United States Design Patent**
Bartl

(10) **Patent No.:** **US D604,662 S**
(45) **Date of Patent:** **** Nov. 24, 2009**

(54) **OBJECT MADE OF GLASS OR GEMSTONE**

D549,610 S * 8/2007 Prechtl D11/90
D560,542 S * 1/2008 Prechtl D11/90
D594,369 S * 6/2009 Mosmann D11/89

(75) Inventor: **Richard Bartl**, Terfens (AT)

* cited by examiner

(73) Assignee: **Swarovski Aktiengesellschaft**, Triesen (LI)

Primary Examiner—R. Seifert

(**) Term: **14 Years**

(74) *Attorney, Agent, or Firm*—Wenderoth, Lind & Ponack, L.L.P.

(21) Appl. No.: **29/311,004**

(57) **CLAIM**

(22) Filed: **Dec. 5, 2008**

The ornamental design for an ornamental object made of glass or gemstone, as shown and described.

(30) **Foreign Application Priority Data**

DESCRIPTION

Jun. 23, 2008 (EM) 000956347-0004

FIG. 1 is a bottom view of the invention;

(51) **LOC (9) Cl.** **11-02**

FIG. 2 is a top view of the invention;

(52) **U.S. Cl.** **D11/89**

FIG. 3 is a right side view of the invention;

(58) **Field of Classification Search** D11/1-2,

FIG. 4 is a front view of the invention;

D11/26-29, 89-92; 63/26-28, 32

FIG. 5 is a left side view of the invention;

See application file for complete search history.

FIG. 6 is a back view of the invention; and,

(56) **References Cited**

FIG. 7 is a perspective view of the invention.
